ROOF-MOUNTED AIR CONDITIONING UNIT

Walter E. Woods and Paul E. Hammann, Bettendorf,
Iowa, assignors to American Air Filter Company, Inc.,
Louisville, Ky.

Filed Feb. 4, 1972, Ser. No. 223,817

Term of patent 14 years

Int. Cl. D23—04

U.S. Cl. D23—139

Fig. 2

Fig. 3

Fig. 4

FIG. 1 is a perspective view of the roof-mounted air conditioning unit, showing our new design;

FIG. 2 is a top view of the roof-mounted air conditioning unit of FIG. 1;

FIG. 3 is an elevational view of the roof-mounted air conditioning unit of FIG. 1; and

FIG. 4 is an end view of the roof-mounted air conditioning unit of FIG. 1.

We claim:

The ornamental design for a roof-mounted air conditioning unit, substantially as shown and described.
